PATENTED JAN. 22, 1907.

F. WACKENHUTH.
INTERNAL COMBUSTION ENGINE.

APPLICATION FILED APR. 19, 1905.

UNITED STATES PATENT OFFICE.

FREDERICK WACKENHUTH, OF NEWARK, NEW JERSEY.

INTERNAL-COMBUSTION ENGINE.

No. 841,830.

Specification of Letters Patent.

Patented Jan. 22, 1907.

Application filed April 19, 1905. Serial No. 256,339.

To all whom it may concern:

Be it known that I, FREDERICK WACKENHUTH, a citizen of the United States, and a resident of Newark, in the county of Essex and State of New Jersey, have invented a new and Improved Internal-Combustion Engine, of which the following is a full, clear, and exact description.

The invention relates to internal-combustion engines particularly useful in burning liquid fuels, but operative in connection with gaseous or solid fuels, if desired.

The object of the invention primarily is to secure complete combustion of fuel, at the same time avoiding loss of heat and radiation through the cylinder-walls and contamination of the fresh charge by the products of previous combustion within the cylinder.

The invention involves various other features of major or minor importance, all of which will be fully set forth hereinafter, and particularly pointed out in the claims.

Reference is had to the accompanying drawing, which represents as an example the preferred embodiment of the invention, which drawing is a vertical section of the engine, illustrating by broken lines the governor and valve operating devices.

According to the form of the invention here illustrated the engine is provided with a frame 10, on which is mounted the crank-shaft 11.

12 indicates a connecting-rod which is joined to the crank and to a cross-head 14, the cross-head operating in suitable guides, one of which is shown at 15 in the drawing.

16 indicates a piston-rod attached to the cross-head, and 17 indicates the body of the piston, which operates in the cylinder 18.

19 indicates the cylinder-head.

20 indicates a half-speed shaft driven from the crank-shaft 11 and carrying any suitable devices 21 and 22 for actuating the fuel-pump and exhaust-valve.

45 The cylinder 18 is provided with a refractory non-conducting lining 23, which is preferably of porcelain or the like and which is formed in the cylinder, as shown, and finished true on its inner surface, so as to permit the piston to operate in the cylinder in the usual manner. At the base of the cylinder an annular gutter 24 is formed, adapted to contain a lubricating liquid fed by a connection 25, located under a suitable reservoir or dropper 26. The body of the piston

may be of any desired material, but preferably of porcelain, and below the packing-rings an annular dipper 28 is arranged. The dipper is intended to enter the gutter 24 when the piston is at the bottom center, and then as the piston rises a certain quantity of the liquid is elevated with the dipper, and upon the succeeding downstroke the inertia of the lubricant causes the dipper to leave the lubricant and the side of the piston throws the lubricant out against the cylinder, thus constantly lubricating the same.

The body 17 of the piston is provided with two valve-seats 29 and 30 in the upper face thereof, and below these valve-seats a number of ports 31 are formed which communicate with the valve-seats and form passages through the body of the piston. The valve-seats 29 and 30 are concentric, and co-acting with these seats is a valve 32, which has a concentric inner and outer surface arranged to coact with the seats 29 and 30, as shown. The web of the valve 32 is formed with ports 33 therein, and the valve has a stem 34, which plays in the rod 16 and in an opening in the shield 35. Said shield 35 is fastened to the body of the piston by means of bolts 36, and the shield is preferably constructed of three sheets or laminations, the bottommost one of which is formed of steel, the middle one of asbestos, and the upper one of iron. Said shield protects the valve 32 from the intense heat in the combustion-chamber of the engine and also serves to limit the opening movement of the valve. The shield is perforated to permit air to flow freely through it from the ports 29. When the piston descends upon the suction-stroke, the atmospheric pressure lifts the valve 32 from its seat and permits air to flow through the lower end of the cylinder and past the valve into the working chamber. In connection with this valve it will be observed that by furnishing the valve with two seats and permitting the fluid to flow around the outer edge of the valve and through the opening 33 a double passage is given for the air, giving large areas and permitting great volumes to pass the valve in a given time. 100 Fastened to the body 17 of the piston outside of the valve 32 is an annular case 37, formed of sheet-steel and filled with a mass 38 of asbestos. From this case 37 an annular shield 39 rises, this shield having a diameter slightly less than the maximum

enter a corresponding cavity 40 in the cylinder-head 19, without, however, contacting with the side walls of the said cavity.

The cylinder-head 19 is provided with a flange 41, which is fastened by bolts 42 to a flange 43 on the cylinder 18. Said parts 41 and 43 are provided with annular flanges 44 and 45, of which the flange 45 has a tapered edge and the flange 44 a grooved edge receiving the point of the flange 45, so as to form a tight connection between the cylinder and its head through the medium of these parts. Said parts are relatively thin, however, and owing to this permitting the radiation of a minimum amount of heat from the cylinder-head of the cylinder. Within the ribs 44 and 45 a mass 46 of asbestos is arranged, and this asbestos is confined by a narrow annular rib 47, projecting outwardly 20 from the cylinder-head, as shown.

The cylinder-head is formed with a frustoconical combustion-cavity 48, which matches with the inner surface of the case 37, forming an essentially pear-shaped chamber, as the drawing shows. The combustion-cavity 48 of the cylinder-head has an asbestos lining 49, confined by a sheet-steel covering 50. This prevents the dissipation of heat from the combustion-space. 51 indicates a port formed in the cylinder-head and adapted to communicate with a source of air under pressure, this port leading to a chamber 52 in the cylinder-head directly above the shield 50. Formed integral with or fastened to the shield 50 is a combustion-tube 53, which is formed of iron or steel or other suitable material and which communicates with the chamber 52 by openings 54 in the top of the tube. Said chamber communicates with the top of the cylinder-head combustion-space by means of openings 55 and is provided at its lower end with interior prongs 56, which in the operation of the engine become incandescent for the purpose which will hereinafter appear.

57 indicates the source of fuel, which in the present instance is supposed to be liquid fuel, such as kerosene-oil. This passage 57 is controlled by a check-valve 58, which opens into the pump-chamber 59. In this chamber a plunger 60 operates. The pump-plunger is driven from the device 22 on the shaft 20 through a suitable connection (indicated by the broken lines 61) and a vibrating link 62, in which a slide 63 is arranged, said slide being in connection with one of the plunger-driven elements 61. The link 62 is slotted to receive the slide 63, as indicated at 64, and at the inner end of said slot an enlargement 65 is formed, in which the slide is adapted to be received. When the slide is in position within this enlargement 65 of the slot 64, free movement of the link will be permitted without driving the pump-plunger. 65 By adjusting the slide to other positions

along the link the stroke of the plunger may be varied so that a larger or smaller quantity of fuel is forced from the chamber 59.

66 indicates a governor of any desired type and which is operated in synchronism with the engine and connected to the slide 63, so that the stroke of the fuel-pump is under the control of the governor. From the pump-chamber 59 a passage 67 leads to a crossing passage 68, formed vertically in the cylinder-head and leading to the upper end of the combustion-tube 53. The passage 68 is fitted with a plug 69, and this is formed with a groove 70, running longitudinally from the passage 67 to a point near the combustion-tube 53. At this point the plug 69 is formed with an annular groove 71, communicating with the groove 70, and below this groove the end of the plug is reduced, leaving a minute tubular passage between the reduced end of the plug and the surrounding walls of the passage 68. It will be observed, therefore, that upon the pumping stroke of the plunger 60 a quantity of fuel will be forced through the passage 67, groove 70, and into the groove 71, and from this groove the fuel will be forced in a tubular spray into the combustion-tube 53. Upon the suction-stroke of the plunger 60 a quantity of fuel is drawn past the valve 58 into the pump-chamber 59, and this suction-stroke of the plunger 60 is arranged to take place synchronally with the suction-stroke of the working piston 17, so that the pressures on the liquid fuel in the chamber 59 and passages 67, 70, and 71 are balanced and the fuel will not at this period flow into the cylinder. Passing from the chamber 52 is an exhaust-port 72, which leads into a chamber 73, formed in the cylinder-head. In this chamber operates a piston-valve 74, having a frusto-conical surface bearing against a seat 75, formed at the lower end of the chamber 73. This valve, it will be observed, is balanced in so far as concerns the pressure within the working cylinder and may be freely opened without overcoming said pressure. From the lower end of the chamber 73 a port 76 passes, conducting the exhaust to the atmosphere or to any other desired point. Formed in the cylinder-head, near the bottom of the combustion-chamber 48 thereof, is a port 77, which crosses the annular chamber 40 and is normally closed by any desired means—for example, by a plug 78.

In the operation of the engine, assuming the parts to be constructed and assembled as above described, the piston should be moved to the bottom crank center and the plug 78 removed. A quantity of liquid fuel should be forced under a pressure of any desired sort through the passages 57, 59, 67, 70, and 71 into the combustion-tube 53, and a volume of air should be passed under pressure through the passage 51 into the chamber 52 130

and from this chamber through the openings 54 into the combustion-tube, where it mixes with the fuel spray, forming a combustible mixture, which may be ignited through 5 the port 77. This mixture will burn with a blue flame, the products of combustion passing out through the open port 77. This operation should be continued until the combustion-tube becomes incandescent, where- 10 upon the flame should be extinguished and the air-supply cut off from the port 51. Then upon operating the engine a quantity of fresh air will be drawn into the cylinder past the valve 32 and the pump will spray the 15 liquid fuel into the incandescent combustion-tube. The air will circulate into this tube through the openings 55 thereof, and the fuel will be ignited, burning with a Bunsen flame. In the operation of the engine the prongs 56 20 are subjected to the heat and will insure the ignition of the fuel. After the fuel is cut off the gases of combustion expand in the cylinder, imparting the working stroke to the piston. The piston then returns and the valve 25 74 is opened, forcing out from the cylinder the products of combustion, excepting such as lie in the combustion-chamber of the engine. Upon the following downstroke of the piston the valve 32 is lifted and a quantity 30 of fresh air is admitted to the cylinder below the small quantity of burned gases left in the combustion-space. Upon the first part of the compression or return stroke of the piston the exhaust-valve 74 is again opened, so as to 35 permit the rest of the burned gases in the cylinder to be expelled. After this is done the exhaust-valve is closed, and the compression of the air within the cylinder follows until the piston reaches the top center and a second 40 charge is admitted, the operation being then repeated as before described.

While the engine is particularly intended for liquid fuel, as described, it may by immaterial alterations be transformed into a gas or 45 even pulverized-fuel engine.

Having thus described the preferred form of my invention, what I claim as new, and desire to secure by Letters Patent, is—

1. An internal-combustion engine having 50 a liquid-fuel pump arranged to discharge such liquid fuel into the working cylinder, a working piston operating in the working cylinder, and means for driving the pump in synchronism with the working piston to cause 55 the pump and working pistons to exert their suction-strokes simultaneously.

2. An internal-combustion engine having a working cylinder, a working piston operating therein, a pump-chamber having valve- 60 less communication with the working cylinder, a plunger operating in the cylinder, and means for driving the plunger, said means causing the pump-plunger to exert its suction-stroke simultaneously with the suction- 65 stroke of the working piston.

3. An internal-combustion engine having a combustion-tube therein adapted to receive the fuel at one end, and to discharge it into the working cylinder at the other end, said tube having an air-inlet opening adjacent to the receiving end, the tube also having an interior prong adjacent to its discharge end. 70

4. An internal-combustion engine using a liquid fuel, having a fuel-inlet passage and a 75 plug in the passage, the plug having a longitudinal groove leading to the discharge end, and an annular groove communicating with the first-named groove and located adjacent to said discharge end, the end of the plug beyond 80 the annular groove being reduced and spaced from the walls of the passage, for the purpose specified.

5. An internal-combustion engine having a cylinder and cylinder-head, one of said 85 parts having an annular rib, and the other of said parts having an annular rib with a groove in the edge receiving the edge of the first-named rib.

6. An internal-combustion engine having 90 a cylinder and cylinder-head, one of said parts having an annular rib, and the other of said parts having an annular rib with a groove in the edge receiving the edge of the first-named rib, whereby to join the head and cylinder, and the head having a second annular rib inwardly of the first-named rib forming a space adapted to receive a non-conducting 95 material.

7. An internal-combustion engine having 100 a piston with an annular metallic case attached to the face thereof and adapted to receive a non-conducting material, and an annular shell projecting from the case and adapted to enter the annular cavity in the cylinder-head. 105

8. An internal-combustion engine having a combustion-tube in its working chamber, adapted to receive fuel at one end and discharge it from the other end, said tube having interior metallic prongs, for the purpose 110 specified.

9. An internal-combustion engine having a combustion-tube in its working chamber adapted to receive fuel at one end and discharge it from the other end, said tube having interior metallic prongs, for the purpose 115 specified, located directly adjacent to the discharge end of the tube.

10. An internal-combustion engine using a liquid fuel, having a fuel-inlet passage, and a 120 plug in said passage, said plug having a groove therein leading to the end of the plug adjacent to the working cylinder of the engine, and said end of the plug being reduced to space it from the walls of said passage. 125

11. An internal-combustion engine having a cylinder, a cylinder-head formed with a combustion-chamber therein, and with an annular cavity outward from the combustion-chamber and communicating with the 130

- cylinder, a working piston operating in the cylinder, an annular metallic shell fastened to the piston and adapted to enter said annular cavity of the cylinder-head when the piston is in its inner position, a non-conducting material lining the walls of the combustion-space of the cylinder-head, and a sheet-metal covering for retaining said non-conducting material.
12. An internal-combustion engine having a cylinder, a cylinder-head formed with a combustion-chamber therein, and with an annular cavity outward from the combustion-chamber and communicating with the cylinder, a working piston operating in the cylinder, an annular metallic shell fastened to the piston and adapted to enter said annular cavity of the cylinder-head when the piston is in its inner position, a non-conducting material lining the walls of the combustion-space of the cylinder-head, a sheet-metal covering for retaining said non-conducting material, and an ignition-tube located in said combustion-space and adapted to receive the fuel as it is entered thereinto, said ignition-tube being sustained by the said sheet-metal covering.
13. An internal-combustion engine having a working cylinder and head, the head having a combustion-chamber, a non-conducting material lining said chamber, a sheet-metal covering engaging the non-conducting material to retain it in place, and an ignition-tube located in the working chamber and sustained by said metallic covering.
14. An internal-combustion engine having a working cylinder and head, the head having a combustion-chamber therein, and an annular cavity outward from the combustion-chamber, a non-conducting material lining the combustion-chamber, a sheet-metal covering holding said material in place, an ignition-tube located in the combustion-chamber and sustained by said sheet-metal covering, an annular metallic case attached to the face of the piston and adapted to contain a non-conducting material, and an annular metallic shell projecting from the case and adapted to enter the said annular cavity of the cylinder-head.
15. An annular combustion-engine having a working cylinder and head, the head hav-
- ing a combustion-chamber therein, an annular cavity outward from the combustion-chamber, a non-conducting material lining the combustion-chamber, a sheet-metal covering holding said material in place, an ignition-tube located in the combustion-chamber and sustained by said sheet-metal covering, an annular metallic case attached to the face of the piston and adapted to contain a non-conducting material, an annular metallic shell projecting from the case and adapted to enter the said annular cavity of the cylinder-head, the piston having a port therein inward of said annular metallic case, and an automatic valve commanding the port and opening into the combustion-chamber.
16. An internal-combustion engine having a cylinder, a piston operating therein, an annular metallic case attached to the face of the piston and adapted to contain a non-conducting material, the piston having a port therein inward of said annular case, and an automatic valve commanding the port and opening into the combustion-chamber of the engine.
17. An internal-combustion engine having a cylinder, a piston operating therein, an annular metallic case attached to the face of the piston and adapted to contain a non-conducting material, the piston having a port therein inward of said annular case, an automatic valve commanding the port and opening into the combustion-chamber of the engine, a perforate shield located opposite the valve of the piston, and means for attaching said shield to the piston.
18. An internal-combustion engine having a working cylinder and piston, the cylinder having admission and exhaust ports, and also having a starting air-admission port to permit heating the interior of the cylinder and an auxiliary exhaust-port for the gases of combustion during the heating of the cylinder, and a valve commanding the main exhaust-port.
